UNITED STATES PATENT OFFICE.

EDWIN E. CODMAN, OF PROVIDENCE, RHODE ISLAND, ASSIGNOR TO
R. BLACKINTON & CO., OF NORTH ATTLEBORO, MASSACHUSETTS, A FIRM.

DESIGN FOR A HANDLE FOR SPOONS, FORKS, OR SIMILAR ARTICLES.

SPECIFICATION forming part of Design No. 37,388, dated April 4, 1905.

Application filed March 9, 1905. Serial No. 249,278. Term of patent 7 years.

To all whom it may concern

Be it known that I, EDWIN E. CODMAN, a subject of the King of Great Britain, residing at Providence, in the county of Providence and

5 State of Rhode Island, have invented a new, original, and ornamental Design for the Handle of a Spoon, Fork, or Similar Article, reference being had to the accompanying drawings.

10 Figure 1 is a view of the obverse side of the handle, showing my design; and Fig. 2 is a reverse view of the same.

What I claim as new, and desire to secure by Letters Patent, is—

The ornamental design for the handle of a spoon, fork or similar article, as shown.

EDWIN E. CODMAN.
